INTERNAL EXPANSION ENGINE

Walter T. Kinslow, Santa Ana, Calif.

Continuation of application Serial No. 219,679,
 July 18, 1938. This application April 3, 1939,
 Serial No. 265,675

5 Claims. (Cl. 123—50)

My invention relates to internal combustion engines and more particularly to engines of the two stroke variety; the invention to which this application relates being a continuation of my co-pending application filed July 18, 1938, Serial No. 219,679.

An object of the present invention is the provision of an engine in which the maximum compression of fuel occurs when the piston crank is substantially past dead center, thereby increasing the moment of leverage of the piston rod and crank at the time of firing.

A further object is to provide such an engine in which a positive intake of fuel gas is had at atmospheric pressure without resort to compression of the gas.

Other objects and advantages of this invention will be made manifest in the following description taken in connection with the accompanying drawings, in which:

Fig. 1 is a vertical sectional view taken through a preferred embodiment of the invention.

Fig. 2 is a vertical sectional view taken on the line 2—2 of Fig. 1.

Fig. 3 is a horizontal sectional view taken on the line 3—3 of Fig. 1.

Figs. 4 to 7 are sectional views similar to Fig. 1 showing successive operative positions of the engine of my invention.

Referring specifically to the drawings, a preferred embodiment of engine 10 of my invention includes a casting 11 having a crank case 12 formed thereon. Provided by the upper portion of the casting 11 is a water jacketed block 13 having a bore 14. Formed in opposite sides of the block 13 are intake and exhaust ports 16 and 17 respectively, these communicating with intake and exhaust pipes 18 and 19 respectively, the exhaust pipe 19 having a check valve 20 provided therein to permit the exhaust of gases from the port 17 into the pipe 19 and to prevent the return of gases therethrough as will be described hereinafter.

Journalled in bearings 25 and 26, as shown in Fig. 2, is a crank shaft 27 having a piston crank pin 28 and a pair of cylinder crank pins 29 formed thereon, the crank pins 29 being positioned 90° in advance and having one half the amount of throw of the crank pin 28 as seen in Fig. 4. Mounted on the bearing 25 is a timer 32 which includes a housing 33 having terminals 34 and 35 thereon. Fixed on the end of the crank shaft 27 within the housing 33 of the timer 32 is a rotor 37 adapted to conduct intermittent charges of electricity from the terminal 34 to the terminal 35. Extending from the terminal 35 to a switch

S, shown in Fig. 2, is a wire 36. Extending to the timer 32 from a suitable source of high-tension current is a pair of wires 38 and 39, the wire 38 being connected to the terminal 34 and the wire 39 being grounded. Mounted on top of the block 13 is a cap 40 having an insulated terminal 41 mounted thereon, the latter being joined with the switch S by a wire 42.

Slidable within the bore 14 of the block 13 is a sleeve cylinder 45 connected with the crank pins 10 29 of the shaft 27 by connecting rods 46. Formed integral with the upper end of the cylinder 45 is a head 48 having a spark plug 49 mounted therein, the latter having an elongated terminal 50 which extends upwardly close to the terminal 41 15 of the cap 40. Formed at opposite sides of the sleeve cylinder 45 are intake and exhaust ports 52 and 53 respectively, these being positioned for registration at suitable intervals with the intake and exhaust ports 16 and 17 respectively of the 20 block 13.

Within the cylinder 45 is a piston 54 connected with the crank pin 29 by a connecting rod 55, a combustion chamber 56 being formed in the sleeve cylinder 45 between the upper end of the piston 54 and the head 48 of the cylinder.

Operation

In Fig. 1, the sleeve cylinder 45 and piston 54 30 of the engine 10 are shown in firing position, the combustion chamber 56 having been reduced to its smallest volume so as to compress the fuel gas contained therein. While in the firing position shown in Fig. 1, the crank pin 28 is disposed 35 at an angle of about 45° past dead center at substantially its maximum moment of torque relative to the crank shaft 27. At this time, the spark plug 49 is fired by contact of the rotor 37 of the timer 32 with the terminal 35, the current passing through the wire 36, switch S, wire 42 and into the terminal 41 where the current jumps to the terminal 50 to fire the plug 49.

From the firing position shown in Fig. 1, the piston 54 moves downward on its power stroke 45 driving the crank shaft 27 in a clockwise direction as viewed in Fig. 1. When the piston 54 has moved to the position in which it is shown in Fig. 4, the exhaust port 53 of the sleeve cylinder 45 is uncovered by the piston 54 permitting the burnt gases to pass through the ports 53 and 17 50 into the exhaust manifold 19, the pressure of the exhaust gases lifting the check valve 20, thus enabling the gas to pass thereby. After the exhaust of the burnt gases as shown in Fig. 4, the piston 55

54 continues downward and the sleeve cylinder 45 starts upward, these combined movements increasing the volume of the combustion chamber 56 and decreasing the pressure therein well below atmospheric.

It will be noted that while the exhaust ports 53 and 17 are in registration until the sleeve cylinder rises to the position in which it is shown in Fig. 5, the return of combustion gases from 10 the exhaust pipe into the combustion chamber 56 is prevented by the closing of the check valve 20 immediately following the outward rush of these gases. This check valve is not necessary in the operation of my motor, but is preferably 15 used to facilitate smooth idling.

When the piston 54 moves from the position in which it is shown in Fig. 5 to that shown in Fig. 6, the intake port 52 of the sleeve cylinder 45 is uncovered permitting the sub-atmospheric pressure in the combustion chamber to rapidly suck fuel gas inward through the aligned ports 16 and 52. It will be seen in Fig. 6 by noting the relative positions of the crank pins 28 and 29 that, following the intake of fuel into the chamber 25 56, the sleeve cylinder 45 moves upward while the piston 54 is at bottom dead center, the sleeve cylinder 45 thus closing the intake port 16 before the piston 54 moves upward sufficiently to compress this fuel.

30 The piston 54 and sleeve cylinder 45 now move to the compression position shown in Fig. 7 which just precedes the firing position shown in Fig. 1 and already described.

After the engine 10 has been running a short 35 while it will continue to run without any electricity. The fuel gases are subjected to such pressures and temperatures as will crack the fuel fractions of lower gravity and induce self-ignition. This ignition regularly takes place at or 40 shortly following the peak of compression.

When operating the engine of my invention, it is preferable to employ a light grade of fuel in starting. When the engine has been running a short a period as from five to fifteen seconds, 45 however, it may be switched over to a heavier fuel.

The trapping of a portion of the burnt gases in the upper portion of the cylinder and the introduction of the fuel at the lower end of the 50 combustion chamber beneath these trapped gases produces, when the entire charge is compressed, which is just before firing, a stratification with the burnt gases disposed in the layer above the compressed mixture of fuel. It is the present 55 theory that this condition is responsible for the self-ignition above referred to.

When starting the motor, however, the self-ignition does not occur and it is necessary to employ an electric spark to ignite the fuel charge. 60 I found that for this spark to be effective it must take place at a point within the lower stratifying layer of gases in which the fuel mixture is found. Fig. 1 shows the parts of the motor 10 in firing position and this illustrates the location 65 of the electrodes of the spark plug 49 at the time the distributor 42 causes the spark to be produced between them.

Because of the self-ignition above referred to, the engine of my invention consumes a much 70 greater portion of the carbon molecules normally released in burning hydrocarbon fuels. It also operates with equal efficiency on various grades of gasoline, distillates and even fuel oil.

It is estimated that the pressure to which the 75 fuel and retained combustion gases are subjected

to produce the cracking and self-igniting above referred to ranges from 180-220 lbs. per sq. in.

I claim as my invention:

1. In a two-stroke internal combustion engine, the combination of: a block having a bore, a 5 crank chamber and bearings; a crank shaft journaled in said bearings, said shaft having primary and secondary crank pin means; a sleeve cylinder slidably mounted in said bore; means connecting said primary pin means to said sleeve 10 cylinder; a piston slidable in said sleeve cylinder to form a combustion chamber in said sleeve cylinder; means connecting said piston to said secondary pin means, the throw of said primary crank pin means being substantially less than 15 said secondary crank pin means and following the latter substantially ninety degrees, there being exhaust ports in said sleeve cylinder and said block which register while uncovered by said piston and while said combustion chamber is 20 expanding rapidly and has a substantial amount yet to expand incidental to the power cycle; and fuel supply means including intake ports in said sleeve cylinder and said block which register and are opened by said piston when the expansion of 25 said combustion chamber is substantially at its maximum.

2. In a two-stroke internal combustion engine, the combination of: a block having a bore, a 30 crank chamber and bearings; a crank shaft journaled in said bearings, said shaft having primary and secondary crank pin means; a sleeve cylinder slidably mounted in said bore; means connecting said primary pin means to said sleeve

cylinder; a piston slidable in said sleeve cylinder 35 to form a combustion chamber in said sleeve cylinder; means connecting said piston to said secondary pin means, the throw of said primary crank pin means being substantially less than 40 said secondary crank pin means and following the latter substantially ninety degrees, there being exhaust ports in said sleeve cylinder and said block which register just as said ports are uncovered by said piston and with said sleeve cylinder in substantially its lowermost position 45 and while said combustion chamber is expanding rapidly and has a substantial amount yet to expand incidental to the power cycle; and fuel supply means including intake ports in said sleeve cylinder and said block which register and are 50 opened by said piston when the expansion of said combustion chamber is substantially at its maximum.

3. In a two-stroke internal combustion engine, the combination of: a block having a bore, a 55

crank chamber and bearings; a crank shaft journaled in said bearings, said shaft having primary and secondary crank pin means; a sleeve cylinder slidably mounted in said bore; means connecting said primary pin means to said sleeve 60 cylinder; a piston slidable in said cylinder to form a combustion chamber in said sleeve cylinder; means connecting said piston to said secondary pin means, the throw of said primary crank pin means being substantially less than 65 said secondary crank pin means and following the latter substantially ninety degrees, there being exhaust ports in said sleeve cylinder and said block which register while uncovered by 70 said piston and while said combustion chamber is expanding rapidly and has a substantial amount yet to expand incidental to the power cycle; check valve means preventing resurgence of exhaust gases through said exhaust ports as the latter are closing; and fuel supply means 75

including intake ports in said sleeve cylinder and said block which register while uncovered by said piston after said exhaust ports have opened and closed.

- 5 4. In a two-stroke internal combustion engine, the combination of: a block having a bore, a crank chamber and bearings; a crank shaft journalled in said bearings, said shaft having primary and secondary crank pins means; a sleeve cylinder slidably mounted in said bore; means connecting said primary pin means to said sleeve cylinder; a piston slidable in said sleeve cylinder to form a combustion chamber in said sleeve cylinder; means connecting said piston to said secondary pin means, the throw of said primary crank pin means being substantially less than said secondary crank pin means and following the latter substantially ninety degrees, there being exhaust ports in said sleeve cylinder and 10 said block which register just as uncovered by said piston and with said sleeve cylinder in substantially its lowermost position and while said combustion chamber is expanding rapidly and has a substantial amount yet to expand incidental to the power cycle; check valve means preventing resurgence of exhaust gases through said exhaust ports as the latter are closing; and fuel supply means including intake ports in said sleeve cylinder and said block which register 15
- 20
- 25

while uncovered by said piston after said exhaust ports have opened and closed.

5 5. In a two-stroke internal combustion engine, the combination of: a block having a bore, provided with intake and exhaust ports extending through the wall thereof, said intake port being disposed below the level of said exhaust port; a check valve preventing the inward passage of gases through said exhaust ports; a reciprocal cylinder in said bore having a head provided on one end thereof, said cylinder having intake and exhaust ports extending through the wall thereof, the intake and exhaust ports of said cylinder communicating with the intake and exhaust ports respectively of said block during reciprocation of said cylinder in said block; a reciprocal piston in said cylinder, said intake and exhaust ports of said cylinder being successively opened and closed by said piston during reciprocation thereof; primary and secondary crank means; rod means connecting said primary and secondary crank means with said piston and said cylinder respectively, said primary and secondary crank means being so related as to cause said cylinder and said piston to move in opposite directions following the opening of said exhaust port and prior to the opening of said intake port. 10 15 20 25

WALTER T. KINSLOW.
